(57) **CLAIM**

The ornamental design for a transceiver tag, as shown and described.

DESCRIPTION

FIG. 1 is an isometric view of a transceiver tag showing our new design.

FIG. 2 is a front view thereof.

FIG. 3 is a back view thereof.

FIG. 4 is a right side view thereof.

FIG. 5 is a left side view thereof.

FIG. 6 is a top view thereof; and,

FIG. 7 is a bottom view thereof.

Dashed or broken lines depict portions of the depicted article that form no part of the claimed design and are included to provide further context for the claimed design. The broken-out sections represented by the gaps between the heavy-weight dash-dot-dash lines are included to show that the transceiver tag has no specific height, width, or length.
